E. L. BENSON

THERMOSTATICALLY OPERATED SWITCH

Filed Sept. 3, 1921

Fig. 1.

Fig. 2.

UNITED STATES PATENT OFFICE.

ERNEST L. BENSON, OF PUEBLO, COLORADO.

THERMOSTATICALLY-OPERATED SWITCH.

Application filed September 3, 1921. Serial No. 498,334.

This invention relates to alarms of the automatic type which will indicate the presence of fire or any attempt to enter through a window or door thus acting simultaneously as a fire alarm and a burglar alarm.

Another object of the invention is to provide means for adjustably supporting a thermostat so as to regulate the amount of heat which will be necessary to actuate the same to an extent sufficient to cause the signal to operate.

Another object of the invention is to provide a circuit closing device which is actuatable by thermostats or some mechanical mechanism such as a window or door.

A still further object of the invention is to generally improve upon alarms of this nature by providing a device which will be of extremely simple and efficient construction, one which may be manufactured at a comparative low cost and will be reliable in operation.

With the above and numerous other objects in view, the invention consists of certain novel features of construction and the combination and arrangement of parts as will be herein-after more fully described and claimed.

In the drawings:

Figure 1 is an end elevation of the container showing the alarm mounted therein;

Figure 2 is a longitudinal section through the container showing the alarm situated therein;

Figure 3 is a top plan view of the container showing the alarm therein; and,

Figure 4 is a detail view showing the construction of the adjustable bracket for the thermostat.

Referring to the drawings in detail, it will be seen that 1 indicates a container which may be of any preferred construction and in the present modification is provided with a battery compartment 2 having situated therein the dry cells 3. The larger compartment 4 contains the thermostat and circuit closing means and also the alarm. The alarm 5 is preferably audible in the nature of the ordinary electric bell which is in the circuit with the batteries 3 through the electric wires 6. A circuit closing means is disposed in the

circuit formed by the wire 6 and is mounted on a support 7. This circuit closing mechanism consists of a push button switch 8 of conventional construction and a lever 9 which is fulcrumed at 10 to the support 7 so as to have one end 11 situated in front of or adjacent the push button 12 of the push button

switch 8. The other end of the lever 9 is connected to a cable 13 which may be attached to a door or window so that when the same is opened or raised this cable 13 will be pulled upon so as to actuate the lever 9 whereby the end 11 will push inwardly upon the push button 12 so as to close the switch 8 thereby sounding the audible alarm 5 as will be readily understood.

An adjustable thermostat bracket is situated directly in front of the support 7 and consists of a pair of spaced bars 14 having the feet 15 which are fixed to the bottom of the container 1. These bars 14 are each provided with a slot 16 extending transversally thereof adjacent its top so as to receive the bolster 17 which is mounted in the bar 18. This bar 18 is provided with a sleeve 19 at its top for receiving a screw 20 which supports the thermostat 21. A pair of lugs 22 are formed adjacent the lower end of the bar 18 so as to rest on top of one of the rods 14 as shown to advantage in Figure 4. The bolster 17 is provided with the usual thumb screw so that when the same is tightened the bar 18 will be held in firm engagement with the rods 14. If it is desired to adjust the thermostat 21 this thumb screw is unscrewed and the bar 18 may be moved in its relation either rearwardly or forwardly upon the rods 14.

The thermostat 21 is of conventional construction and is provided with a projecting contact member 23 which when the thermostat is expanded by the heat will engage the end 11 of the lever 9 so as to force the same in engagement with the push buttons 12 so as to close the switch 8 for sounding the audible alarm 5.

The above description and the accompanying drawing relate to the preferred embodiment of my invention, but of course it will be understood that numerous changes may be made in the construction and arrangement of parts without departing from the spirit of the invention as set forth in the accompanying claim.

Having thus described my invention what I claim as new is:

An adjustable thermostat mounting, comprising a bracket including a pair of members one of which is adapted to be mounted in upright position and is provided with a slot, the other member being arranged in overlapping end relation to the slotted member, a bolt extending through the other mem-

ber and through the slot, a nut for said bolt co-operating therewith to maintain the members in adjusted position with relation to one another, lug members carried by said 5 other member and adapted to rest upon the top edge of the slotted member, and a thermostat mounted on said other member whereby it may be adjusted in spaced relation with

respect to an associate instrument, said slotted member having the slot formed there-¹⁰ in transversely of the upper end thereof to permit horizontal adjustment of said thermostatic.

In testimony whereof I affix my signature.

ERNEST L. BENSON.
